DESIGN FOR A FAN STAND

Auguste J. Bouthiller, Henryville, Quebec, Canada

Application February 16, 1938, Serial No. 75,198

Term of patent 3½ years

To all whom it may concern:

Be it known that I, Auguste J. Bouthiller, a citizen of Canada, residing at Henryville, in the Province of Quebec and Dominion of Canada, have invented a new, original, and ornamental Design for Fan Stand, of which the following is a specification, reference being had to the accompanying drawing, forming part thereof.

Fig. 1 is a front elevational view of a fan stand showing my new design; Fig. 2 is a side elevational view of the same according to the arrow 2 in Fig. 1, and Fig. 3 is a sectional view on the line 3—3 of Fig. 2.

I claim:

The ornamental design for a fan stand, as shown.

AUGUSTE J. BOUTHILLER.
